UNITED STATES PATENT OFFICE

WILLIAM M. POWERS, OF MINNEAPOLIS, MINNESOTA, ASSIGNOR TO POWERS SIGN CO., INC., A CORPORATION OF SOUTH DAKOTA

STREET MARKER

Application filed August 6, 1930. Serial No. 473,400.

This invention relates to street markers or other signs, the primary object of the invention being to provide a street marker or sign of such a construction that it may be 5 illuminated by an external light, thereby providing a street marker or sign which may be used in connection with an ordinary street light or other external lighting means.

An important object of the invention is to 10 provide an adjustable reflector positioned within the casing, means being provided for adjusting the reflector to various angles so that the light rays from the illuminating means may be projected through the front 15 wall of the casing.

A still further object of the invention is the provision of a casing so constructed that it will be absolutely water and dust proof.

With the foregoing and other objects in 20 view, which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

Referring to the drawings:

30 Figure 1 is a front elevational view of a street marker constructed in accordance with the invention.

Figure 2 is a sectional view taken on line 2—2 of Figure 1.

35 Figure 3 is a sectional view taken on line 3—3 of Figure 1.

Figure 4 is a sectional view taken on line 4—4 of Figure 1.

40 Referring to the drawings in detail, the casing includes a box-like structure formed of end walls 5, front wall 6, downwardly inclined top 7, rear wall 8, and bottom 9.

45 As shown, the end walls are formed with extensions at their upper ends, the extensions being indicated by the reference character 10, the front wall 6 being formed with an outwardly extended portion 11 and upwardly and rearwardly extended portion 12 to be fitted over the extensions 10 of the end walls. The end walls are formed with in-

wardly extended flanges 13 that cooperate with the inwardly extended portion 12 of the front wall in providing a support for the transparent member 14, forming the top. This top or transparent member 14 is disposed at an oblique angle with respect to the front wall of the device, so that light rays from various angles may be absorbed or projected into the casing, thereby insuring the complete illumination of the interior of the casing. Removable flange members 15 are secured to the rear wall 8, and embrace portions of the lower edge of the member 14 to hold the member 14 in position.

In order that the casing will be made dust proof, felt packing members 16 are disposed between the inwardly extended portion 12 and flanges 13. It might be further stated that the upper edge of the rear wall 8, extends downwardly as at 16', and the translucent member 14 is of a width to extend beyond the outer edge of the downwardly extended portion 16' of the rear wall, so that water or moisture collecting on the member 14 will be drained therefrom and directed to a point exteriorly of the casing.

The front wall of the casing is formed with cut out portions defining letters, so that when light rays are directed through the cut out portions, words will be outlined to indicate the streets or matter to be displayed.

Secured to the rear surface of the front wall is a translucent member 17, which is held in position by the frame 18, bolted to the front wall by means of the bolts 19. Felt packing members 20 are disposed between the frame 18 and front wall of the casing, to insure a dust proof connection therebetween.

90 Mounted within the casing, and supported in the bearings 21, is a shaft 22 formed with an offset portion 23 that provides a support for the reflector 24 that has its front edge loosely abutting the front wall of the casing, so that as the shaft 22 is swung within its bearings the reflector will be raised or lowered, to properly adjust the reflector with respect to the light rays, to illuminate the characters of the front wall. One end of

the shaft 22 extends at right angles as at 23', where it engages notches in the keeper 24'. The right angled portion 23' of the shaft 22 is disposed adjacent to an opening 5 formed in one end wall of the casing, so that a key may be positioned in the opening to engage the right angled portion, with the result that when the key is rotated, the shaft will be rotated to adjust the reflector.

19 The key opening in the end wall, is normally closed by the threaded plug 25, so that moisture and other foreign matter will be excluded from the interior of the casing.

From the foregoing it will be obvious 15 that due to the construction shown and described, the forward edge of the top will extend to such a position that it will guard the front of the casing to prevent moisture from entering the casing at this point.

20 It will further be seen that the adjusting mechanism is so housed within the casing, that adjustment of the reflector, by unauthorized persons, will be prevented.

In the use of the device it is contemplated 25 to support the casing directly under a street lamp, in such a way that the light rays from the lamp will enter the casing through the transparent top, and be projected through the cut out portions of the front 30 wall of the casing.

I claim:

1. An illuminated sign comprising a casing, a front wall having cut out portions, forming a part of the casing, a shaft mounted within the casing, said shaft having an offset supporting portion, a reflector loosely mounted within the casing and resting on the supporting section, a keeper having notches disposed within the casing, one end 40 of the shaft extending at right angles and adapted to engage within the notches to hold the shaft in its positions of adjustment, and a transparent top forming a part of the casing, to allow light rays to pass there- 45 through.

2. An illuminated sign comprising a casing having a front wall formed with cut out portions defining words, and having a transparent top to permit light rays to enter the casing, a shaft mounted for movement within the casing, a reflector resting on the shaft for directing light rays forwardly through the front wall of the casing, said shaft adapted to move to adjust the reflector, end 50 walls forming a part of the casing, one of said end walls having a key opening to receive a key to operate the shaft.

3. An illuminated sign comprising a casing embodying end members, a front wall 60 having cut out portions defining words, a transparent top to permit light rays to enter the casing, bearing members within the casing, a shaft operating within the bearing members and having an offset supporting 65 section, a reflector resting on the supporting

section, said shaft having a right angled end portion disposed within the casing, means cooperating with the right angled end portion to restrict movement of the shaft, and said casing having a key opening to receive 70 a key to rotate the shaft.

4. An illuminated sign comprising a casing, said sign having a front wall formed with cut out portions defining words, a transparent top disposed at an oblique angle 75 with respect to the front wall to project light rays inwardly to the interior of the casing, a rear wall and end walls forming a part of the casing, and a bottom forming a continuation of the rear wall.

In testimony that I claim the foregoing as 80 my own, I have hereto affixed my signature.

WILLIAM M. POWERS.
